UNITED STATES PATENT OFFICE.

FRANCIS R. FLYNN, OF NEW YORK, N. Y.

COMBINED TIMED LOCK AND RECORDER

1,114,348.

Specification of Letters Patent.

Patented Oct. 20, 1914.

Application filed January 27, 1914. Serial No. 814,608.

To all whom it may concern:

Be it known that I, FRANCIS R. FLYNN, a citizen of the United States, residing in the city of New York, borough of Bronx, county of Bronx, and State of New York, have invented a certain new and useful Combined Timed Lock and Recorder, of which the following is a specification.

This invention is a combined timed lock and recorder, and the object of the invention is to permanently record, in a simple, efficient, and exact manner, the precise times when a lock is operated.

Speaking more specifically, the invention embodies improvements whereby a lock, installed *e. g.*, on a door, is so arranged in conjunction with a time train and time recording mechanism, that, when the lock is operated to either open or close the door, the precise time of said operation is recorded on a chart.

Among the novel features embodied in the invention may be mentioned the following: first, the employment of a chart supporting drum on which is wound a removable time chart; second, an improved time chart drum whereby the employment of padding beneath the time chart is obviated, and pronounced advantages secured; third, means coöperating with the drum and operable by the movement of the bolt of the lock for the purpose of causing said means to record on the chart the times of operation of the lock; fourth, bolt operating means coöperating with mechanism for locking the bolt in either its locked or drawn positions, whereby surreptitious operation of the bolt is precluded; fifth, means coöperating with the locking mechanism whereby complete locking or unlocking operations and consequent recording of time is imperative upon the slightest movement of said mechanism; and sixth, novel means for securing a chart to its supporting drum.

In one of its practical forms the invention embodies a time train, a drum adapted to support a chart, said drum being driven at a constant speed by the time train, a marker adapted to coöperate with the chart on the drum, said marker being mounted for movement longitudinally of the axis of the rotation of said drum, said movement being imparted also from the time train, whereby the coöperating marker and chart are moved in synchronism, in combination with a bolt of the type which is adapted to be slid to

and fro for the purpose of locking or unlocking the closure to which it is applied, means operable by the sliding movement of the bolt for actuating the marker and thus cause designations to be made upon the chart. I also provide means which may be utilized, if desired, to clearly distinguish the records of the locking operations from those of the unlocking operations of the bolt.

Features of the invention other than those specified will be apparent from the following description, read in conjunction with the accompanying drawings.

In the accompanying drawings I have illustrated different practical embodiments of the invention, but the constructions shown therein are to be understood as illustrative, only, and not as defining the limits of the invention.

Figure 1 is a front elevation of the preferred embodiment of my invention, the casing being removed in the interest of clearness. Fig. 2 is a side elevation of the mechanism shown in Fig. 1, said view being taken from the left hand side of Fig. 1. Fig. 3 is a horizontal, transverse, section taken on line 3-3 of Fig. 1. Figs. 4 and 5 are like sections taken on line 4-4 of Fig. 1, Fig. 4 illustrating the mechanism disclosed when looking in the direction of the single arrow, and Fig. 5 that perceived when looking in the direction of the double arrow. Figs. 6 and 7 are a plan and elevation, respectively, of the locking bolt. Fig. 8 is a section taken on line 8-8 of Fig. 2, illustrating means to preclude tampering with the lock. Fig. 9 illustrates a plan view of the chart receiving drum, which I employ, detached from the retaining mechanism. Fig. 10 is a central, vertical section through said drum, illustrating, in dotted lines, my preferred method of applying the chart to the drum. Fig. 11 is a face view of one form of chart which I employ. Fig. 12 is a vertical section through the casing taken on line 12-12 of Fig. 4, and illustrates means whereby a key-hole in the casing may be closed upon the closing of the door of said casing. Fig. 13 is a detail of the bolt actuating and locking means. Fig. 14 is a like view illustrating means coöperating with the bolt, whereby the locking and unlocking operations, as recorded on the chart, are clearly differentiated. Fig. 15 is a fragmental side elevation, looking from the right hand side of

Fig. 1, illustrating a certain wiper and its operating cam, hereinafter more fully described. Fig. 16 is a front elevation of a modified construction of my invention, the front wall of the casing being removed in the interest of clearness. Fig. 17 is a vertical section taken on line 17-17 of Fig. 16. Figs. 18 and 19 are transverse horizontal sections taken on lines 18-18 and 19-19, respectively, of Fig. 16. Fig. 20 is a fragmental detail of the chart carrying drum, and indicating mechanism, said section corresponding to the line 17-17, Fig. 16. Figs. 21 and 22 are fragmental plan views showing different operative positions of the chart indicating mechanism, and the actuating means therefor. Fig. 23 is a face elevation of the mechanism illustrated in Fig. 21, and Fig. 24 is a transverse section through the chart perforating mechanism therein shown.

Referring to Figs. 1 to 15, inclusive, of the drawings, wherein the preferred embodiment of the invention is illustrated, A denotes, what I prefer to designate, the back plate of the device. On this plate the mechanism is mounted, whereby it may be fastened to a door or other closure. Intermediate the ends of the plate A, and on the same side thereof, is a pair of forwardly projecting brackets, a , a' . These brackets are tightly secured to the back plate, and carry a rotatable spindle B, which rests in a journal on the bottom bracket a' , and passes upwardly through the upper bracket a , and is thereabove provided with a bevelled pinion, d . Between the brackets, loosely mounted on the spindle, B, is a chart carrying drum heretofore mentioned. Exterior of either end of said drum, collars, b , b' , are fixed on the spindle B, and intermediate these collars and the corresponding ends of the drum are positioned resilient spring members c . Thus, although the drum is loosely mounted, as far as rotation is concerned, on the spindle B, it is manifest that the tension exerted by the resilient members, c , will cause said members to coöperate with the ends of the drum after the manner of a friction clutch. Accordingly, if power were supplied to the spindle, B, through the pinion, d , the friction clutches would transmit the rotary motion to the drum under normal conditions. However, should any difficulty arise in the operation of the drum, or if it is desired to reverse the mechanism for any means whatever, the power exerted by the friction members would be insufficient to hold the drum and its spindle against relative rotation, and said drum would be allowed to slip sufficiently to preclude breakage or allow adjustment.

According to my invention the drum should be revolved at a constant speed, and accordingly, I provide a suitable time train or clock mechanism, D, which is mounted on

the upper bracket a , and so positioned relative to the bevelled pinion, d , that the operation of the time train transmits rotary motion to the drum, C, through the pinion, d .

70

Mounted on the lower end of the drum, coaxial therewith, and set off therefrom on the posts, f , is a gear, F, which gear meshes with a pinion, E, fixed on a worm, e, which is positioned parallel to the spindle, B, and 75 is journaled at either ends in the brackets, a , a' . On the worm, e, is mounted a rocking arm or lever, G, and this arm is operated by means of a cam spindle mounted between the brackets, a and a' , which cam 80 spindle engages with the power arm of the lever, G. The working arm of the lever is provided with a threaded tap into which is screwed, for adjustment, a needle, pencil point, or other suitable recording mechanism which, when the rocking arm is oscillated, will serve to indent or otherwise suitably mark a chart wound upon the drum, C.

85

While many forms of charts may be employed, the one next to be described has been 90 found to give very good results, and a clear, unmistakable, exact record of data desired. This chart, I, is generally formed from a strip of paper, light cardboard, or other material and has formed upon its face, section lining extending both longitudinally and transversely thereof. The transverse are preferably, substantially, perpendicular to longitudinal edges of the chart and, in the preferred form, designate a predetermined length of time. The total length of the chart, i. e., the circumference of the drum, C, preferably represents 12 hours, so that when the chart is wound upon the drum, 2 revolutions of the chart constitute 100 a day of 24 hours. For convenience in reading the chart, it is divided up longitudinally into hour, half-hour, and ten minute spaces, and, since it is desirable to have the chart extend over a period of several days, these 105 days are laid off by the longitudinal lines, each two spaces representing a day. It will be seen from the chart illustrated in Fig. 11 that there are 16 vertical spaces, which denote the a. m. and p. m. of 8 days. While, 110 if desired, the names of these days could be printed opp site the respective a. m. and p. m. spaces thereof, it is impractical, from a commercial standpoint, since all the charts would not be installed in the different machines on the same day. It is desirable that, when a chart is put into a machine, the plotting or marking operation start at the top of the chart so that it would not be necessary to return to the machine and put in a new chart for a week or eight days. Consequently, a small circle, designated, i, is provided on the face of the chart so that when the chart is put into a machine, the workman may mark a numeral 1, 2, etc., desig- 115 120 125 130

nating respectively, the first, second and third days etc., of the week. Thus, if the numeral 1, is found in the circle, *i*, anyone looking at the chart, and conversant with the same, would understand that the chart reads from a Sunday. If the numeral 2 were found, it will be understood that the chart was inserted on Monday, etc.

The longitudinally extending lines on the chart are not parallel to the edge thereof, but are parallel to each other, and slope downwardly so that when the chart is wound upon the drum, each line on the chart will match with the succeeding line thereon, so as to extend from near the top of the chart in the form of an entire and unbroken helix from the top to the bottom of the drum. In other words, the second line will be a continuation of the first, the third a continuation of the second, etc. Thus, an a. m. space will, after twelve hours, or one rotation of the drum, become a p. m. space, and subsequently an a. m. space, etc., alternating every twelve hours.

There are many ways in which the chart, *I*, may be installed upon the drum, but, as it is quite necessary that the longitudinal edges of the chart be parallel with the top and bottom faces of the drum, I have found that the following method of securing the chart in place is decidedly practical. Drum, *C*, is provided with a slit, *j*, extending from the upper to the lower edge thereof, and the upper face of said drum, adjacent to the slit, *j*, is provided with an enlarged aperture, *j'*, to allow the passing of a pin or bodkin through the upper wall of the drum into the interior thereof. In securing the chart to the drum, the drum is turned so that the slit, *j*, is at the front of the machine, and within easy access of the operator. The end of the chart is then wound or looped about the pin or bodkin, *J*, and the bodkin inserted into the aperture, *j'*, in the top of the drum, whereupon the chart will pass edge-wise, downwardly through the slit, *j*, in the drum, after the manner illustrated in Fig. 10 of the drawings. The chart is provided at its other end with a small transparent tab, *i'*, preferably gummed on its rear side. After this tab has been moistened, the operator rotates the drum, whereupon the chart is wound thereon. For facilitating the securing of the gummed tab, *i'*, I preferably provide a wiper, *K*, mounted on the back plate, *A*. Thus, as the drum is rotated, the tab passes under the wiper, and is pressed down and secured in place. I preferably make the wiper of width coextensive with the width of the chart, so that during the operation of wiping the tab in place, the chart is smoothed out, and all wrinkling thereby precluded.

The wiper is preferably in the form of a broad leaf spring, *K*, which is secured to the

back plate by means of screws or the like. This wiper is normally out of engagement with the drum, but is adapted to be impelled there against by a cam, *k*, pivoted between the brackets, *k'*, and operable by a handle, *k''*. Thus when it is desired to install a chart on a drum, the cam is operated to impel the wiper against the drum, as shown in dotted lines in Fig. 3. At all other times, however, the cam is in its idle position, as shown in full in said figure, and the wiper is thus allowed, by virtue of its tension, to remain free from engagement with the drum.

Although I do not restrict myself to the form of drum illustrated in the drawings, I have found said drum to be extremely efficient. In the form of mechanism illustrated the designating or marking member is in the form of a perforating pin, *g*, and it pricks holes in the chart at the desired times. To facilitate the pricking of these holes, the drum may be padded, but this padding has its drawbacks, in that it is difficult to correctly maintain the chart around a padded drum in its proper position, hence the improved drum. The improved drum, as shown more particularly in Fig. 10, is provided with a continuous helical channel leading from near the top of the drum to close to the bottom thereof, and forming between its successive convolutions a comparatively sharp rib, *c'*. The pitch of this helical rib, *c'*, is equal to the pitch of the helix formed by the lines on the chart when the same is in place on the drum, with the result that, when the chart is properly positioned, the rib, *c'* will be directly beneath the longitudinal lines on the chart so that when the needle pricks between these lines, the point thereof is allowed to pass through the chart, and into the channel on the circumference of the drum. Thus a clear, distinct prick may be made without endangering the point of the perforating pin, *g*, by its coming into contact with the hard face of the drum. Moreover, by the use of the improved drum, all padding is obviated, and the chart may be wound upon the drum with accurate precision.

From the foregoing description, it will be manifest that the time train drives the drum, *C*, and the worm, *e*, in synchronism, *i. e.*, as the drum is revolving, the worm is turning to lower the rocking arm in timed relation to the rotation of the drum. Consequently, when the chart is positioned on said drum, the relative velocity of the drum and the rocking arm is such that the perforating needle will travel downwardly over the successive, helical convolutions of the chart. In the structure shown, the chart is adapted to make one revolution every twelve hours, and, since the chart is adapted to record eight days, the movement of the rocker arm and perforating needle from the top of the

chart to the bottom thereof, tracking all the while, the convolutions of the chart will occupy the space of 8 days. Manifestly the perforating needle and the chart are so relatively positioned, at all times, that, if the rocking arm is operated it will invariably perforate said chart between the adjacent longitudinal lines thereof indicating the a. m. or p. m. of the day during which the same is made. Although it is not absolutely essential, I prefer to mount a light leaf spring, c^2 , on the bracket, a , which leaf spring is adapted to rest on the upper surface of the drum, and steady the operation thereof.

According to this invention the arm, G, carrying the perforating pin, g , is rocked to produce perforations in the chart whenever the bolt of the lock, which coöperates therewith, is moved to or fro to lock or unlock the closure with which it is associated. The operation of registering these movements of the bolt will next be described.

The bolt, L, is mounted on the back plate, A, below the bracket, a' , and is retained against removal by a keeping plate, l , secured to the back plate by screws, l' . Formed in the bolt, L, is a rack, M, with which coöperates a pinion, m , fixed at the lower end and beneath the bracket, a' , on the cam spindle, H. Thus, when the bolt is slid back and forth to its locked or unlocked positions, such movement imparts rotary motion to the cam spindle, H, with the result that the working end of the rocking arm, which carries the perforating needle, is moved toward and away from the chart carrying drum. A leaf spring, g' , is secured on the rocking arm, and, at all times, presses against the cam spindle, H, for the purpose of retaining the power arm of the rocking lever, g , in engagement with the cam spindle (see Fig. 3). The size of the pinion, m , and length of the rack are such, however, that the movement of said bolt to either of its operative positions will give the cam shaft but one complete turn. Accordingly, when the bolt is moved to the operative position, the rocker arm is oscillated once to perforate the chart, and correspondingly, when the bolt is returned to its unlocked position, the rocker arm is given another oscillation to once more perforate the chart, (see dotted line position of rocker arm, G, in Fig. 3).

The means for imparting movement to the bolt, L, is embodied in the plug, N, which passes through the aperture in the back plate, A, and is provided with a wing, n , adapted to engage a notch, l^2 , in the upper edge of the bolt. A tubular sleeve, O, extends through the thickness of the door and into its outer end is inserted ordinary key reception means, a . g ., barrel, o , of a yale lock with the usual wards and plungers.

The rotary portion of said barrel, o , is provided, at its end, with a polygonal blank, o' , which is secured against rotation thereto, and is adapted to engage with a slot, o^2 , in the adjacent end of the plug, N. Thus, when the key is inserted into the barrel, o , and turned, the rotary motion will be imparted through the blank, o' , to the plug, N, which movement will swing the wing, n , thereof, thereby resulting in sliding movement of the bolt, L.

During the foregoing operation of shifting the bolt to its locked or unlocked positions, the rack, M, pinion, m , cam spindle, H, and rocker arm, are coöperating to produce the record of such movement on the chart. In order to preclude any attempt to "beat" the lock, it is deemed advisable to provide means, whereby the perforations designating the locking of the bolt may be clearly distinguishable on the chart, from those corresponding to the unlocking of said bolt. I, therefore, provide means whereby the perforations, formed on a locking operation, are in different planes from the perforations occasioned by the unlocking of said bolt. This means is embodied in a carrier plate, P, which is pivoted to the back plate, A, by means of the screw, p . One end of this plate is provided with arms, p' , p^2 , which engage with the worm, e , in such manner that, when the plate, P, is oscillated in one direction, it will serve to depress the worm, while in a counter direction will cause the elevation of said worm. The mechanism is so adjusted that, in the elevated position, the marker will traverse the chart near the upper edge of the space over which it is traveling, while on the depressed movement, if the marker is operated, it will mark the chart near the lower edge of said space. Thus, the locking operations of the bolt will be made along the upper edge of the space, and the unlocking operations along the lower edge thereof, with the result that they are clearly differentiated. The swinging plate, P, is automatically operated upon the turning of the plug, N, by means of an extending trip or lug, n' , formed on the wing, n , of said plug. This trip engages with an eccentric, p^3 , formed in the plate, P. Manifestly, when the plug, N, is operated, as aforesaid, to unlock or lock the bolt, the trip, n' , will coöperate with the eccentric to depress and lower the worm alternately, according to the movements occasioned by the locking or unlocking of the bolt.

Many doors are so hung that, the free edges thereof do not fit tightly into the doorway, and in some locks it is possible to but partly withdraw the bolt in order to open the door. In a device of this class, it is essential that, every movement of the bolt, no matter how slight, need be recorded, and

with this end in view, I have provided means whereby the complete locking or unlocking operations, and consequent recording of the time thereof is imperative upon the slightest movement of said mechanism. This means is illustrated, more particularly in Fig. 8, as embodying a pawl and ratchet arrangement. The ratchet is formed upon the back end of the plug, N, and the pawl, o^s , is mounted on the projection, o^t , of the back plate, A. The pawl is of a length greater than the distance from its point of pivoting to the base of the teeth of the ratchet, and cannot, therefore, be positioned in a direct line with the ratchet wheel, except at one portion thereof where the teeth are cut away, as at o^s , and this cut away portion is so positioned relative to the wing, n, on the plug, N, that, the pawl can only occupy this cut away portion when the bolt is entirely locked or unlocked. Thus, when the operation of moving the bolt is started, the pawl swings to one side of the center line, passing through the axis of the plug and the point of pivoting of the pawl, and, upon the turning of the plug, engages with the successive teeth on the ratchet. The springs, o^s , retain the pawl in engagement with said teeth. Thus, after the operation of moving the plug and the consequent movement of the bolt has been started, the pawl will engage with the teeth of the ratchet, and preclude the return operation of the bolt, until the same has been moved its entire travel, and the consequent recording accomplished.

In the operation of the lock to throw or withdraw the bolt, the operator inserts the key and gives it a fraction of a revolution more than a complete turn. This brings about the desired result of locking or unlocking the closure, and brings the pawl to the cut-away portion of the ratchet, so that upon the withdrawal of the key, the parts are left in such position that the key may be inserted again when it is desired to reverse said operation, and said operation immediately proceeded with. It will thus be noted that it is necessary to give the plug, N, a little more than one complete revolution, in order to slide the bolt its entire travel, because of the lost motion between the pawl and ratchet.

The plug, N, is provided with a small projection n^2 , which, when said plug is rotated, extends into the path of the bolt, b^2 , and the bolt is provided with notches, b^3 , immediately adjacent, and on either side of the notch, b^2 . Thus, when the plug is turned and the wing, n, disengaged from the notch, b^2 , the projection, n^2 , immediately engages one of the notches, b^3 , and the bolt is, practically at all times, engaged by some part of the plug, N. Thus, if the plug is retained against return movement, the bolt is like-

wise retained. Consequently, in the normal operation of the lock, i. e., the imparting of a single revolution to the key, the bolt, when the key is withdrawn, will be left in retained form, i. e., it cannot be surreptitiously operated with a screw driver or the like to shift the bolt to another position. The proper key must necessarily be employed to complete the operation before the same can be reversed.

In the practical operation of the present invention a chart is inserted into the drum, as heretofore described, the prime mover of the time train, e. g., a spring is wound up, and the mechanism is left to operate for a week or eight days. At the end of a week the inspector returns, removes the weekly record chart from the drum, and installs a new one in its place. At the same time turning back the worm, e, to bring the rocker arm at the top of the chart in the position to start next week's record. To facilitate this turning back of the worm I preferably form a beveled gear, Q, on the drum spindle, B, with which beveled gear is associated a pinion, Q', mounted on the bracket, a', in a bearing, q', and having a spindle with a polygonal end with which a key is adapted to coöperate. Manifestly, the turning of the key on the spindle of said pinion will impart movement through the beveled gear, Q, the gear, F, and pinion, E, to the worm, e, whereby the rocker arm may be elevated, as desired. In order that said key may be inserted into the casing, an aperture, q^2 , is formed therein (see Fig. 12) and this aperture is normally closed by a plate, Q^2 , one arm of which is engaged by the door, A', of the casing, when the same is swung shut. Thus, when the door, A', is closed and locked, the plate, Q^2 , cannot be shifted from the outside of the casing for the purpose of surreptitiously inserting the key to tamper with the lock operating mechanism. However, when the door is open, the plate, Q^2 , may be swung away from the aperture, q^2 , as shown in dotted lines in said figure, and the key may be readily inserted. I wish it understood that, although I have described special means for returning the lock arm to its initial operative position, the same is not absolutely necessary, since the drum may readily be revolved by hand to bring about the desired result. In either instance the drum is allowed to revolve conversely to the impelling action of the time train, because of the fact that said drum is not positively connected to the drum spindle, B, but simply frictionally connected thereto.

Having fully stated the preferred embodiment of the invention and the operation of the several distinct features thereof, the complete operation may be briefly set forth as follows:—The chart having been properly positioned on the drum, and secured in

130

place by the wiper, and the clock mechanism having been started, the door of the casing is closed and locked, and for the next eight days or a week the mechanism becomes a sentinel of the closure with which it is associated. When it is desired to lock the door, the key is inserted into the barrel, o_1 , of the lock, and the plug, N , operated to swing the wing, n , thereon and slide the bolt into locked position. Simultaneously with the movement of the bolt the rack, M , imparts rotary motion to the cam spindle, H , with the result that the chart is perforated, thereby recording the time of the sliding of the bolt. Before said bolt has, however, completed its travel, the trip, n' , on the plug, N , is engaged with the eccentric portion, p^3 , of the plate, P , and elevates the worm so that the perforating needle is in the position to make the next perforation.

The operation of sliding the bolt its entire travel, either into locked or unlocked position, requires a little more than a complete revolution of the key, and the plug, N , is so adjusted, relative to the bolt, that when the bolt is in its locked or unlocked position, the projection n^2 , on said plug will coöperate with one of the notches, n^8 , on the bolt. Thus, in the locking or unlocking operation of the bolt, the operator gives the key a trifle more than one revolution, so that, when the key is withdrawn from the wards of the lock barrel, the pawl o^6 , will be in the cut-away portion of the ratchet and the projection n^3 , will be in engagement with one of the notches, l^5 , of the bolt. Consequently, when the operation of locking or unlocking the bolt is completed, the parts of the lock are left, upon the withdrawal of the key, in such position that the key may be inserted again when it is desired to reverse the operation, and the said reversed operation immediately proceeded with. However, when in locked or unlocked position, the bolt is adequately retained against surreptitious movement, by means other than the lock barrel, by the engagement of the projection n^2 , with one of the slots, l^5 , in the bolt, said plug being maintained against shifting by virtue of the friction between itself and its bearing.

I have set forth in the foregoing description, one particular form of chart embodying both transverse and longitudinally disposed markings. I have found, however, that the longitudinal markings are not absolutely compulsory in the manufacture of the chart, and if a chart, devoid of such markings, is placed upon my improved drum, and the drum rotated with the wiper, K , in contact with the chart, the pressure of said wiper coöoperating with the comparatively sharp edge of the rib on the drum will adequately mark the drum with longitudinally extending creases, which cor-

respond to the inked sectioning illustrated in the drawings. This arrangement and method of marking the chart will give an absolutely invariable record. I have also illustrated the worm as adapted to longitudinal movement subject to movement of the bolt. I may, however, make the worm stationary, and correspondingly move the drum instead. The form shown is the best, however, and I have illustrated it for this reason. Another advantage which will be apparent is the fact that the lock is adapted for use in conjunction with both right and left hand closures, it being manifest that, by the provision of the extra rack, M' , the bolt may be turned end for end, so that the rack, M' , will coöperate with the pinion, m .

Having now described, at length, the mechanism, function and operation of the preferred form of the invention illustrated in Figs. 1 to 15, inclusive, attention is directed to Figs. 16 to 24, wherein is shown a modified form of the invention. This modified form is, in most of its features, very similar to the preferred form; yet, some details are changed, as will be herein-after more fully explained.

In said figures, the casing is designated by the numeral 1, which, like the casing of the preferred form, may be of any desired shape or configuration. In the upper part of the casing is positioned a clock mechanism or time train 2, the operating spindles of which preferably pass through the front of the casing and are provided with means inclosed beneath a glass dial whereby said time train may serve as a clock to advise persons as to the time of day. The time train 2 is provided with a power shaft 3, and a bevel gear 4, which meshes with a bevel gear 5, mounted on a vertical spindle 6, positioned within the casing. On the shaft 6, is mounted the chart receiving drum 7, which is rotatable by the time train through the means of friction clutches 8, 8. As the time train drives the spindle 6, it also rotates a gear 9, secured to said spindle beneath the drum, which gear meshes with a pair of pinions 10, 10, fixed to the spindles of vertically disposed worms 11, 11. Thus, the drum 7, and the worms 11, 11, are rotated in synchronism by the time train 2.

The drum 7 is adapted to carry about its periphery a removable recording sheet 12, similar to the chart 1, hereinbefore mentioned, which chart is adapted to receive records of the movements of the bolt 13, of the locking mechanism through the coöperation therewith of suitable marking mechanism. This mechanism, according to this form of the invention, is mounted on a horizontal bar 14, carried on the worms 11, 11, and by virtue of said worms, movable longitudinally of the axis of rotation of the drum 7.

The marker device consists of three needles penetrating separate orifices therefor, as guides, in bar 14, said orifices being in the same vertical plane. The needles 15, 15, 5 which penetrate the upper and lower orifices, have a connecting bridge 16, at their rear ends, and a spring 17, between the bridge and the bar 14, holds them retracted and out of contact with the time sheet or 10 chart. Similarly, the needle 18, which is intermediate the needles 15, 15, and is entered through alined orifices in the bar 14, and bridge 16, said needle 18, having a head 19, is held out of contact with the time 15 sheet or chart by a spring 20, of less tension than spring 17, lying between head 19, and bridge 16.

The needle points are held normally adjacent to the surface of the time sheet or 20 chart, which they are adapted to strike and impress in the range of their retractile movement. Pressure against the head 19, of the needle 18, will project that needle inwardly without correspondingly moving the 25 needles 15, 15, because the tension of the spring 20, is insufficient to influence spring 17; and pressure against the bridge 16, will project the needles 15, 15, forwardly, independently of the needle 18. Thus, the needle 30 18 can be used to record the movement of the bolt in one direction, and the needles 15, 15, can be used to record the movement of the bolt in the other direction.

The means for actuating the marking 35 needles include a pair of flaps 21, 22, hinged, respectively, to bar 14 at opposite sides of said needles, said flaps being normally out-standing at right angles from bar 14, and being capable, through the agency of coiled 40 springs 23, of returning to said position, in the manner of swinging doors, after being moved in either direction. The flap 21 has a finger-like form and is adapted, when depressed inwardly, to bear against head 19 45 of needle 18, causing the latter to attack and mark the time sheet or chart, but without moving the needles 15, 15. On the other hand, if the flap 22, which is of forked, or bifurcated character, is pressed inwardly, 50 it will straddle the head 19 and will meet and exert pressure upon the bridge 16, thereby forcing the needles 15, 15, against the time sheet or chart, causing the creation of two marks thereon.

55 The flaps 21, 22, are operated by a swinging arm 24, mounted on a vertical, pivotal rod 25, disposed midway between said flaps, the height of said arm covering the range of movement of bar 14, and said arm, in 60 its swinging movements, serving to operatively depress both flaps 21, 22. Said flaps have teeth, 21^a, 22^a, respectively, on their outer surfaces, to permit the inward and forward movement thereover of arm 24, in 65 depressing a flap, but to prevent return of

said arm until the flap has swung out again on its pivot.

The pivotal rod 25, on which the swinging arm 24, is mounted, extends downwardly through the casing and is provided with a 70 segment 26, adapted to coöperate with a rack 27, formed in the bolt 13, whereby sliding movement of the bolt into its locked or unlocked positions will impart movement to the rod 25; for the purpose of operating 75 the chart-marking mechanism.

The means for shutting or retracting the bolt comprises the barrel of an ordinary Yale lock 28, to which is attached a rod 29, fixed to the end of which is a gear 30, coöperating with a rack 31 on the upper edge of the bolt 13. The lock barrel 28, is operable by means of the usual key, whereupon the rod 29 is rotated and the gear 30 utilized to slide the bolt. Hence, when the key is 85 turned in one direction, the bolt will be shot out, while, if turned in the other direction, the bolt will be retracted, these movements being communicated through the rack 27 and segment 26, to the rod 25. The rod 25 90 will operate the swinging arm 24, which will, in turn, coöperate with the flaps 21, 22, to actuate the marking means and produce indications on the chart.

It will be noted that the chart illustrated 95 in this form is slightly different from the chart hereinbefore described, in that, by the arrangement of parts shown, the drum rotates in an opposite direction to the drum of the preferred form. Accordingly, the 100 chart is made conversely. Moreover, the chart 12 is illustrated as a seven-day, instead of an eight-day, chart.

In order that the marking mechanism may be raised to its elevated position for a period of seven days from its initial operation, a worm 32 is positioned to coöperate with the gear 9, to bring about this result, and the spindle of said worm passes outside of the casing and is provided with a finger 110 piece 33, to allow of convenient manipulation of the worm.

From the foregoing description it becomes apparent that both forms of the invention described embody means whereby it 115 is rendered impossible to register less records than operations, and, since the designation on the chart, corresponding to the unlocking of the bolt, is clearly differentiated from that made upon the locking operation 120 thereof, it is impossible to "beat" the lock by a simultaneous locking and unlocking operation. Consequently, the chart will show, at the end of any stated period, a clear, unmistakable and infallible record of 125 every operation of the locking means.

It will be manifest, from the foregoing, that both the preferred and modified forms herein described are very similar in their operations and functions. In fact, some of 130

the features of one form may readily be used in combination with the features of the other form, *e. g.*, the modified construction does not embody my improved means for retaining the bolt against surreptitious movement by means of a screw-driver and the like, as is embodied in my preferred form. It will, therefore, be manifest that this invention embodies many novel and 10 meritorious features and that some of these features may be utilized in the manufacture of devices of the class described without, necessarily, employing all.

Having thus fully described the invention, 15 what I claim as new, and desire to secure by Letters Patent, is:—

1. In mechanism of the class described, the combination of closure locking mechanism, a chart-supporting drum coöperating therewith, a time train for driving the drum, and means coöperating with the drum and with the closure locking mechanism for indicating on a chart, positioned on the drum, the operations of said locking mechanism.

2. In mechanism of the class described, the combination of closure locking mechanism, a chart-supporting drum coöperating therewith, a time train for rotating said drum at a constant speed, and means co- 30 operating with the drum and with one of the movable parts of the locking mechanism for indicating on a chart, positioned on the drum, the operations of said closure locking mechanism.

3. In mechanism of the class described, the combination of locking means, a chart-supporting drum coöperating therewith, a time train for rotating said drum at a constant speed, and means, also driven by the 40 time train, coöperating with the drum and with the locking means and operable by the latter for indicating on a chart, positioned on the drum, the operations of said locking means.

4. In mechanism of the class described, the combination of locking means, a time train, a spindle driven by said time train, a drum loose on the spindle, a yielding connection between said drum and spindle where- 50 by the movement of the spindle is imparted to the drum, and means coöperating with the drum and with the locking means for indicating on a chart, positioned on the drum, the operations of said locking means.

5. In mechanism of the class described, the combination of locking mechanism, a chart supporting drum coöperating therewith, indicating means coöperating with the drum, unitary means for simultaneously

60 rotating the drum and causing the indicating means to traverse a chart mounted on said drum, and mechanism coöperating with the locking mechanism for actuating the indicating means.

65 6. In mechanism of the class described,

the combination of closure locking means embodying a bolt and means for actuating the same, a chart-supporting drum, a time train for imparting rotary motion to the drum, and indicating mechanism movable longitudinally of the axis of rotation of the drum and coöperating with the locking means whereby the operation of said locking means serves to actuate the chart indicating mechanism.

7. In mechanism of the class described, the combination of locking means, a chart-supporting drum, a time train for imparting rotary motion to the drum, indicating mechanism movable longitudinally of the axis of rotation of the drum, and means operable by one of the movable parts of the locking means for causing the indicating mechanism to record the movements of the locking means upon the chart.

8. In mechanism of the class described, a chart-supporting drum, a time train for imparting rotary motion to the drum, a worm positioned adjacent to said drum and parallel to the axis of rotation thereof, means for driving said worm from the time train, and chart indicating mechanism mounted on said worm whereby the indicating mechanism is moved longitudinally of the axis of rotation of the drum simultaneously with the rotary movement of said drum, in combination with locking means, and means coöperating with the locking means and with the chart indicating mechanism, whereby the movement incident to the operating of the locking means imparts movement to the indicating mechanism for the purpose of recording said operation of the locking means upon the chart supported on the drum.

9. In mechanism of the class described, a chart-supporting drum, a time train for imparting rotary motion to the drum, a worm positioned adjacent to said drum and parallel to the axis of rotation thereof, means for driving said worm from the time train, a rocking arm mounted on said worm, and chart indicating means on the rocking arm, whereby said rocking arm is moved longitudinally of the axis of rotation of the drum, simultaneously with the rotary movement of said drum, in combination with a bolt, and a cam coöperating therewith and with the rocking arm whereby the movement of said bolt, in moving the same to its locked or unlocked positions, actuates the cam for the purpose of oscillating the rocking arm for causing the indicating means thereon to record the movement of said bolt upon the chart.

10. In mechanism of the class described, a chart-supporting drum, a time train for imparting rotary motion to the drum, a worm positioned adjacent to said drum and parallel to the axis of rotation thereof, means for driving said worm from the time train, a

- rocking arm mounted on said worm, and chart indicating means on the rocking arm, whereby said rocking arm is moved longitudinally of the axis of rotation of the drum, 5 simultaneously with the rotary movement of said drum, in combination with a bolt, a rack on said bolt, a cam for actuating the rocking arm, and a gear associated with the cam and meshing with the rack on the bolt whereby the movement of said bolt to its locked or unlocked positions operates the cam to oscillate the rocking arm and indicate the movements of said bolt on the chart mounted on the drum.
15. 11. A combined time lock and recorder embodying, in combination, a time train, a drum driven thereby, a cylindrical time chart encircling said drum, a chart marker stationary with respect to the rotation of 20 said chart, means for causing relative movement between the chart marker and the drum in a direction longitudinally of the axis of rotation of said drum, closure locking mechanism, means for actuating said closure locking mechanism, and means, controllable by one of the movable parts of the closure locking mechanism, for actuating the chart marker.
12. A combined time lock and recorder embodying, in combination, a clock mechanism, a drum driven thereby, a cylindrical time chart encircling said drum, a chart marker stationary with respect to the rotation of said chart, means for causing relative movement between the chart marker and the drum in a direction longitudinally of the axis of rotation of said drum, closure locking mechanism, means for actuating said closure locking mechanism, and a rocking rod controlled by the movement of the closure locking mechanism for actuating the chart marker.
13. A combined time lock and recorder embodying, in combination, a clock mechanism, a chart drum driven thereby, a cylindrical removable time chart encircling the periphery of said drum, a chart marker stationary with respect to the rotation of said chart, means for causing relative movement between the chart marker and the drum in a direction longitudinally of the axis of rotation of said drum, closure locking mechanism, means for locking and unlocking said closure locking mechanism, and 55 a rocking rod, controlled by one of the movable parts of the closure locking mechanism, for actuating said chart marker.
14. A combined time lock and recorder embodying, in combination, a clock mechanism, a chart drum driven thereby, a removable time chart about the periphery of said drum, a chart marker stationary with respect to the rotation of said chart, a support for said marker, means synchronized and coaxing with the drum rotation to move the marker support longitudinally of the axis of rotation of the drum closure locking mechanism embodying a bolt and means for actuating the same, and means, controlled by the action of said bolt, for actuating said chart marker.
15. In mechanism of the class described, a rotatable drum adapted to support a time chart, means for driving said drum at a constant speed, a locking member, chart indicating mechanism movable, in timed relation to the rotation of the drum, longitudinally of the axis of rotation of said drum, said indicating mechanism being operable by the movements of the locking member for indicating said movements upon a chart supported on the drum, and means independent of the means for moving the indicating mechanism longitudinally of the axis of rotation of the drum in timed relation to the rotation thereof, co-operating with the locking member whereby the movement of said locking member causes relative longitudinal movement between the rotatable drum and the indicating means for the purpose of clearly differentiating the designations on the chart corresponding to the movements of the locking member to locked position from those corresponding to the movements of the locking member into unlocked position.
16. In mechanism of the class described, a rotatable drum adapted to support a time chart, means for driving said drum at a constant speed, a locking member, chart indicating mechanism movable, in timed relation to the rotation of the drum, longitudinally of the axis of rotation of said drum, said indicating mechanism being operable by the movement of the locking member for indicating said movements upon a chart supported on the drum, and a swinging member, independent of the means for moving the indicating mechanism longitudinally of the axis of rotation of the drum in timed relation to the rotation thereof, operable by the movements of the locking member and co-operating with the indicating means whereby, upon the movement of the locking member, the swinging member impels said indicating means longitudinally of the axis of rotation of the drum for the purpose of clearly differentiating the designations on the chart corresponding to the movements of the locking member to locked position from those corresponding to the movements of the locking member into unlocked position.
17. A combined time lock and recorder embodying, in combination, a rotatable chart drum driven by clock mechanism, and a time chart on said drum, a marker carrier adapted to move over said chart, longitudinally of the axis of rotation of said drum, means for moving said carrier longitudi-

nally of the axis of rotation of the drum, a marker mounted thereon, means for retaining said marker normally retracted, a locking bolt, means controlled by the in and out movements of said bolt to automatically actuate said marker, and means, independent of the means for moving the marker carrier longitudinally of the axis of rotation of the drum, operable upon the movement of the bolt for causing relative movement between the marker and the drum in a direction longitudinally of the axis of rotation of said drum.

18. In mechanism of the class described, a chart supporting drum provided on its circumference with a sharp-edged rib, and means coöperating with said drum whereby the rotation thereof causes said means to operate upon the strip of material, wound on the drum, for the purpose of producing lines on said strip of material corresponding to the sharp edge of the rib on the drum.

19. In mechanism of the class described, a cylindrical chart drum around the circumference of which is adapted to be wound a strip of material, the circumference of said drum being provided with a sharp-edged rib, and means coöperating with said drum whereby, upon the rotation of said drum, said means operates to smooth out the strip on the drum and simultaneously cause said strip to be marked according to the rib on said drum.

20. In mechanism of the class described, a cylindrical chart drum around the circumference of which is adapted to be wound a strip of material, said drum being provided on its circumference with a substantially continuous, helical rib extending for substantially the length of the drum, and means coöperating with said drum whereby, upon the rotation of the drum, said means serves to exert pressure on the strip of material wound thereon for the purpose of marking said strip according to the helical convolutions of the sharp-edged rib on the drum.

21. In mechanism of the class described, a drum around the circumference of which is adapted to be wound a chart suitable for receiving perforated designations, said drum being provided on its surface with a substantially continuous groove, which groove is so disposed upon the drum that the perforations made upon the chart will be coördinate with said groove.

22. In mechanism of the class described, a cylindrical drum around the circumference of which is adapted to be wound a chart suitable for receiving perforated designations, said drum being provided on its circumference with a substantially continuous helical rib so positioned on the drum as to be out of alignment with perforations which may be formed upon the chart.

23. In mechanism of the class described, a cylindrical drum around the circumference of which is adapted to be wound a time chart, said drum being provided on its circumference with a sharp-edged helical rib extending substantially uninterruptedly for substantially the length of the drum, and means for marking designations upon the chart positioned on the drum, said marking means being adapted to coöperate with said drum whereby all designations made upon the chart will be made intermediate the successive convolutions of the helical rib.

24. In mechanism of the class described, a cylindrical drum around which is adapted to be wound a strip of material, perforating mechanism coöperating with the drum, said drum being provided on its circumference with a substantially continuous helical channel extending for substantially the length of the drum, whereby, during the operation of perforating the material, the perforating mechanism is precluded from coming into contact with the surface of the drum.

25. In mechanism of the class described, the combination of locking mechanism, a time train, a chart-supporting member, time-chart indicating mechanism, and means whereby any movement of the locking mechanism renders it imperative to complete the locking or unlocking operation and consequent operation of the chart indicating mechanism.

26. In mechanism of the class described, the combination of locking mechanism, a time train, a chart-supporting drum driven by said time train, chart indicating mechanism coöperating with the time train and the drum and with the locking mechanism, and means governing the operation of the locking mechanism, whereby surreptitious partial operation of the locking mechanism renders it imperative to complete said operation and produce the record of such operation on the chart before a subsequent operation, of the locking mechanism, in a counter direction can be made.

27. In mechanism of the class described, a chart-supporting drum, a time train for rotating said drum, time-chart indicating mechanism coöperating with the chart mounted on the drum, a bolt, means communicating with the indicating mechanism and with the bolt whereby the movements of said bolt are recorded on the chart, and means for actuating the bolt, in combination with means whereby any movement of the bolt actuating means renders it inoperative to reverse any partial movement of said actuating means and renders imperative the completion and the initial movement and consequent operation of the chart recording mechanism.

28. In mechanism of the class described,

5 a cylindrical chart drum around the circumference of which is adapted to be wound a strip of material, the circumference of said drum being provided with a substantially continuous, sharp-edged helical rib extending substantially the entire length of the drum, and a wiper positioned adjacent to said drum, whereby, upon the rotation of the drum, the wiper coöperates with the rib 10 on the drum for the purpose of marking the strip of material wound thereon.

29. In mechanism of the class described, a drum around the circumference of which is adapted to be wound a time chart, said drum being provided upon its circumference with a sharp-edged rib whereby the action of an external force upon the exterior surface of a time chart wound upon the drum will cause said chart to be creased where it contacts with the sharp-edged rib for the purpose of marking circumferential lines on said chart.

30. A casing, for mechanism of the class described, provided with an aperture 25 through which a key may be passed for the purpose of operating mechanism positioned within the casing, a door for said casing, and means, operable by the movement of the door, for closing the aperture in the casing 30 whereby the insertion of the key is precluded when the door of the casing is closed, for the purpose of precluding tampering with the mechanism inclosed within the casing.

31. In mechanism of the class described, 35 the combination of locking means, a chart supporting drum coöperating therewith, a time train for driving the drum, chart indicating means operable by the locking and unlocking of the locking means and movable 40 longitudinally of the axis of rotation of the drum, means for moving the chart indicating means longitudinally of the axis of rotation of the drum in timed relation to the rotation of said drum, and shifting mechanism 45 coöperating with the locking means for causing relative longitudinal movement between the drum and the indicating means upon the operation of said locking means, the relative movement between the drum and indicating means, caused by the shifting mechanism, being entirely distinct and independent 50 of the movement of the chart indicating means and in timed relation longitudinally of the axis of rotation of the drum, whereby 55 by the designations on the chart corresponding to the movements of the locking means into locked position are clearly differentiated from those corresponding to the movements of the locking means into unlocked position.

69 32. In mechanism of the class described, a cylindrical time chart drum provided at one end with an aperture with which communicates a slit passing in the circumference of the drum, and extending longitudinally of 65 the axis of the drum, and a pin adapted to be

inserted into the aperture in the end of the drum for the purpose of retaining the end of a time chart, passed through the slit in the circumference of the drum, to said drum.

33. In mechanism of the class described, a cylindrical time chart drum provided in one end with an aperture and a longitudinally extending slit in its circumference, the aperture in the end of the drum communicating with the slit in the circumference thereof, in combination with a pin adapted to be inserted into the aperture in the end of the drum, and extending longitudinally of said drum, whereby one end of a time chart may be secured to the pin, and the pin inserted into the aperture in the end of the drum for the purpose of securing one end of said time chart to said drum.

34. In mechanism of the class described, a cylindrical time chart drum provided in one end with an aperture and a longitudinally extending slit in its circumference, the aperture in the end of the drum communicating with the slit in the circumference thereof, and a pin adapted to be inserted into the aperture in the end of the drum, in combination with a time chart adapted to be secured at one end to the aforesaid pin, and having at its other end a gummed tab, whereby one end of the time chart may be secured to the pin and the pin inserted into the aperture in the drum for the purpose of securing one end of the chart to said drum and thereafter the chart wound about the circumference of said drum, and the gummed tab thereof secured to a portion of the chart already wound upon the drum.

35. In mechanism of the class described, a cylindrical time chart drum provided in one end with an aperture and a longitudinally extending slit in its circumference, the aperture in the end of the drum communicating with the slit in the circumference thereof, and a pin adapted to be inserted into the aperture in the end of the drum, in combination with a time chart adapted to be secured at one end to the aforesaid pin, and having at its other end a gummed tab, and a wiper coöperating with the drum, whereby one end of the time chart may be secured to the pin and the pin inserted into the aperture in the drum for the purpose of securing one end of the chart to said drum and thereafter the chart wound about the circumference of said drum, and the gummed tab thereof operated upon by the wiper for the purpose of securing said tab to a portion of said chart already wound upon the drum.

36. In mechanism of the class described, a rotatable chart drum around the circumference of which is adapted to be wound a time chart provided at one end with a gummed portion, and a wiper coöperating with said drum whereby, upon the rotation of said drum, the wiper operates to smooth out the

chart and simultaneously secure the same upon the drum.

37. In mechanism of the class described, a rotatable cylindrical chart drum around the circumference of which is adapted to be wound a time chart provided at one end with a gummed tab, and means coöperating with said drum whereby, upon the rotation of the drum, said means operates to smooth out the chart and simultaneously affix the gummed tab for the purpose of securing the chart upon the drum.

38. In mechanism of the class described, a rotatable cylindrical chart drum around the circumference of which is adapted to be wound a time chart, means for securing one end of the time chart to the drum and the free end of said time chart being gummed, and a wiper coöperating with the drum whereby, upon the rotation of said drum, the wiper operates to smooth out the chart upon the drum and simultaneously affix the gummed portion of the chart for the purpose of securing the chart upon the drum.

39. In mechanism of the class described, a rotatable drum adapted to support a time chart, means for driving said drum at a constant speed, a locking member, chart indicating mechanism movable longitudinally of the axis of rotation of the drum and operable by the movements of the locking member, for indicating said movements upon a

chart supported on the drum, and means co-operating with the indicating means and with the locking member whereby the designations on the chart corresponding to the movements of the locking member to locked position are readily discernible from the designations rendered by the unlocking of the locking member.

40. In mechanism of the class described, a rotatable drum adapted to support a time chart, means for driving said drum at a constant speed, a locking member, a worm positioned parallel to the axis of rotation of the drum, means for rotating said worm in synchronism with the drum, chart indicating mechanism mounted on said worm and operable by the movement of the locking member for the purpose of recording on the chart the operations of said locking member, and means whereby the operation of the locking member causes relative longitudinal movement between the worm and the drum for the purpose of differentiating on the chart the locking from the unlocking operations of the locking member.

In testimony whereof I have signed my name to this specification in the presence of two subscribing witnesses.
